UNITED STATES PATENT OFFICE.

AUGUSTUS D. CURTIS, OF CHICAGO, ILLINOIS, ASSIGNOR TO NATIONAL X-RAY
REFLECTOR COMPANY, A CORPORATION OF ILLINOIS.

DESIGN FOR A REFLECTOR HOLDER-BOWL FOR LIGHTING-FIXTURES.

42,573.

Specification for Design.

Patented June 4, 1912.

Application filed December 12, 1911. Serial No. 665,398. Term of patent 7 years.

To all whom it may concern:

Be it known that I, AUGUSTUS D. CURTIS, a citizen of the United States, residing at Chicago, in the county of Cook and State of Illinois, have invented a new, original, and ornamental Design for Reflector Holder-Bowls for Lighting-Fixtures, of which the following is a specification, reference being had to the accompanying drawing, forming part thereof.

The figure is a perspective view, showing my new design.

I claim:

The ornamental design for a reflector holder bowl for lighting fixtures, as shown.

AUGUSTUS D. CURTIS.

Witnesses:

M. M. HEIDEN,
M. M. BOHAN.
